PLATFORM TYPE SHOE

Roy Maling, Chestnut Hill, Mass., assignor to
Margaret A. Maling, Chestnut Hill, Mass.

Application November 4, 1948, Serial No. 58,313.

3 Claims. (Cl. 36—19.5)

1

This invention relates to improvements in platform type shoes and slippers wherein a covered platform base unit is cemented to an upper and an outsole is cemented to the under side of the platform base unit.

In the manufacture of shoes and slippers of the general type to which the invention relates, the attainment of a desired thickness of the platform unit, particularly at forepart regions, heretofore has necessitated inclusion of objectionable bulk of platform stock which has added undesired weight and stiffness to the base units. Public preference dictates that platform base structures should present the appearance of having substantial thickness at forepart regions, yet the buying public is quick to reject a shoe whose forepart lacks an expected easy flexibility, or which gives the feel of excess weight or bulk.

It is among the objects of the invention to provide a platform base structure for shoes and slippers wherein a relatively thin and flexible forepart platform member has covered edges which provide the appearance of a relatively thick platform while simultaneously facilitating the procedure of combining an upper with a platform base unit.

A feature is that a relatively thick bead is stitched around the top margin of a relatively thin forepart member of felt, or the like, and the covering strip for the edges of the platform unit extends over the bead to provide a covered edge whose thickness may be substantially greater than the thickness of the forepart member, and the beaded top surface of the forepart member presents a generally concave juncture surface within whose bead applied cement may be confined, and an upper unit is substantially self-centering when seated within the bead.

Another object is to provide means whereby a substantial bead may be practicably and enduringly secured around the shank and heel regions of a base structure which has substantially its full thickness at these regions made up of wood or the like to which a bead may not be secured directly in any satisfactory manner. The invention provides a carrier sheet, of fibre board or the like, to which the bead may be stitched, and the carrier sheet is cemented to the wooden shank and heel element or elements of the platform, the forward portion of the carrier sheet and the rear portion of the forepart member preferably overlapping each other over the forward portion of the wood shank element, whereby all of these elements may be stapled or otherwise secured together.

2

Yet another object is to provide a substantial upstanding marginal bead all around the top margin of a platform base unit for shoes and slippers, and to effect securement of the bead at the shank and heel regions by stitching it directly to an underlying sheet element which in turn is cemented in covering relation to the upper surface of a solid shank and heel member, said bead constituting a centering means for correct placing of an upper on the base unit, and also serving to obscure the line of cemented juncture between the upper and the base unit.

It is, moreover, my purpose and object generally to improve the structure of platform base units for shoes and slippers, and more especially such units which are designed to be combined with an upper and an outsole by cement.

In the accompanying drawings:

Fig. 1 is a side elevation of a shoe embodying features of the invention;

Fig. 2 is a medial longitudinal cross-sectional view of one form of beaded base unit of a shoe like that of Fig. 1, omitting the outsole;

Fig. 3 is a top plan view of the unit of Fig. 2, but omitting its covering element;

Fig. 4 is a medial longitudinal cross-sectional view of another form of beaded base unit of a shoe like that of Fig. 1, but omitting its covering element;

Fig. 5 is a top plan view of the unit Fig. 4; and

Fig. 6 is a fragmentary medial longitudinal cross-sectional view of the unit of Fig. 4 on a larger scale and including its covering element.

Referring to the drawing, the platform base unit, indicated generally at 10 in Fig. 1, has an upper 12 cemented to its top surface and an outsole 14 cemented to its bottom surface.

According to the invention, the platform base unit 10 has a solid generally wedge-shaped heel element 16, of wood or the like, which has tapering extent forwardly to provide shank curvature for the shoe. A relatively thin forepart member 18, of felt, or comparable resilient material, has its rear edge portion tapering in thickness to a feather edge, and this tapering portion of member 18 overlies the forward edge portion of the solid heel element 16, so that these overlapping portions conveniently may be secured together, as by the staples 20. This provides a structure wherein the thin forepart member 18 is light and highly flexible.

The thin forepart member 18 is built up in thickness around its top margin by the addition of a substantial bead 22 of flexible material which

is stitched at 24 to the member 18 all around the forepart.

In the form of the invention illustrated in Figs. 2 and 3, the bead extends only to or slightly beyond the region of overlapping of member 18 and element 16. A covering element 26 of sheet material is wrapped over the side edges of the unit all around the unit, its upper marginal portion, at the forepart, being turned inward over the bead 22 and cemented at the top side of the unit, and its lower marginal portion being turned inward and cemented to the under side of the unit. By this means, the thin and highly flexible forepart member 18, as seen in Fig. 2, is made to provide the edge appearance of substantially greater thickness, as seen in Fig. 1.

The bead 22 around the top margin of the forepart member 18 of a base unit 10 has additional very distinct advantages in the procedure of combining a base unit with an upper. It constitutes a guide within which cement applied to the top side of the base unit readily may be confined, and it guides the proper centering of an upper on the base unit during the combining operation. After the combining, and in the finished shoe, the covered bead completely obscures the glue line, which is within and behind the bead.

In a preferred form of the invention, the advantages of the bead are provided all around the base unit, as shown in Figs. 4-6. This involves a problem to adequately secure the bead in the shank and heel regions. It is commercially impracticable to secure the bead directly to the thick and bulky solid wood heel element 16. According to the invention, the bead 22' is stitched to the thin forepart member 18, as previously described, and is stitched at 28 to a heel covering sheet element 30 all around the top margin of the latter. Preferably, the forepart member 18 and the heel covering sheet element 30 will overlap a little, as shown at 32, and the bead-securing stitches will secure these overlapping portions together, along each side, so that the member 18 and the element 30, with the bead thereon, may be applied as a pre-stitched assembly to the heel element 16 and be stapled, as at 20'. The base structure of Fig. 4 is covered the same as described in connection with the Figs. 2 and 3 form, but the covering element 26' in this case (Fig. 6), has its top marginal portion turned inward over the bead all around the unit, and the bead, in the completed shoe, obscures the glue line all around the shoe, as well as preliminarily serving for guiding the applying of cement to the base unit and for centering the upper on the base unit, as described in connection with the Figs. 2 and 3 form.

The heel covering sheet element 30 is secured to the heel element by any suitable means, preferably by a coating of cement applied to one or both of the meeting surfaces.

I claim as my invention:

1. In a shoe, a platform base unit comprising a substantially rigid heel element having tapering extent into the shank region of the unit for providing shank curvature, a relatively thin fore-

part element of flexible resilient material extending rearwardly into substantial overlapping relation to the forward end of the rigid heel element, a flexible sheet element for covering the top surface of the heel element, said forepart element and said heel-covering element having appreciable overlapping extent in the shank region of the unit, an upstanding bead on the upper margin of the unit, stitched to the forepart element all around the forepart of the unit and stitched to said heel-covering element all around the rear part of the unit, the bead securing stitches securing the forepart and heel-covering elements together along opposite sides 15 of their said overlapping extents, cement securing the heel-covering element to the top surface of the heel element, and a covering sheet covering the edges of all of said elements and turned inward over said bead, whereby the covered unit has edge thickness substantially greater than the thickness of the said covered elements.

2. In a shoe, a platform base unit comprising a substantially rigid heel element having tapering extent into the shank region of the unit 25 for providing shank curvature, said heel element having a plane under surface, a relatively thin forepart element of flexible resilient material extending rearward into appreciable overlapping relation to the forward end of the heel element, said forepart element having the major portion of its under surface in the plane of the under surface of the rigid heel element, a thin sheet element covering the top surface of the heel element, an upstanding bead stitched 30 to the forepart element all around its upper margin, and stitched to said heel-covering element all around its upper margin, cement securing the heel-covering element to the top surface of the heel element, mechanical means securing all of said elements together at the shank region of the unit, and a covering sheet wrapped over the edges of all of said elements and turned inward over said bead all around the unit, whereby the edge thickness of the unit substantially exceeds the body thickness of said elements throughout the extent of the unit.

3. In a shoe, a platform base unit comprising a substantially rigid heel element having tapering extent into the shank region of the unit 35 for providing shank curvature, a relatively thin forepart element of flexible resilient material, a sheet element for covering the top surface of the heel element, said forepart and heel-covering elements overlapping over the forward portion of the heel element, a bead extending all around the top margin of the unit, being stitched to the forepart element and to the heel-covering element, means securing all three of said elements together at the shank region of the unit, a covering sheet covering the edges of said elements and turned inward over said bead all around the unit, and an upper centered within said bead and cemented to the base unit within and behind said bead.

ROY MALING.
